(57) **CLAIM**

The ornamental design of a range hood, as shown and described.

DESCRIPTION

FIG. 1 is a perspective view of a range hood embodying the present invention;

FIG. 2 is a front view of the range hood;

FIG. 3 is a right side view thereof, with the opposite side being a mirror image;

FIG. 4 is a top view thereof;

FIG. 5 is a bottom view thereof; and,

FIG. 6 is a back view of the range hood.

The broken line showing of environmental structure in FIGS. 1–6 is for illustrative purposes only and forms no part of the claimed design.
